UNITED STATES PATENT OFFICE.

LEE J. VOORHEES, OF BINGHAMTON, NEW YORK, ASSIGNOR TO NATIONAL CARBON COMPANY, INC., A CORPORATION OF NEW YORK.

ILLUMINATING DEVICE.

Application filed June 9, 1920, Serial No. 387,645. Renewed November 21, 1922.

This invention relates to improvements in illuminating devices and more particularly to illuminating devices wherein the light is emitted by an incandescent filament and where a reflector is used to collect the light rays and project them in a regular pencil or beam. More specifically the invention relates to adjustable means for locating the source of light with respect to the reflector to control the form of the pencil or beam of light rays. The invention also relates to portable lamps deriving the energy for their operation from self-contained electric batteries and to devices for protecting the electric bulb from shocks produced by the impact of the heavy battery against it. In its most specific aspect, the invention contemplates a construction of self-contained illuminating apparatus in which an electric bulb may be moved with respect to a reflector for light-rays and in which a buffer for protecting the bulb from destructive impacts will automatically follow the bulb during its movement and be at all times in operative position with respect to the bulb.

The objects of the invention are to provide a simple, cheap and effective construction for focussing an incandescent bulb with respect to a reflector, to provide a buffer or shock absorber to protect the base of an incandescent bulb from destructive impacts and shocks, and to provide a buffer construction which may be used with a focussing construction in such manner that a maximum efficiency will be obtained with a minimum of manipulation of the parts.

I attain these objects by following certain principles of construction, which are embodied in certain specific apparatus herein-after described in connection with the annexed drawings in which:

Fig. 1 shows in section a flashlight embodying my invention.

Fig. 2 shows a section along line 2-2 of Fig. 1, the incandescent bulb being removed.

Fig. 3 shows in perspective the parts 22 and 23 of Figs. 1 and 2,

Fig. 4 shows a modified form of the invention in which it is necessary to remove the lamp-head from the casing to change the focus,

Fig. 5 shows a section along line 5-5 of Fig. 4, and

Fig. 6 shows in perspective the back of the lamp-holding socket of the flashlight

shown in Fig. 4, together with the focussing arm and the cup against the walls of which the end of the focussing arm slides.

In the construction illustrated in Fig. 1, the battery-containing casing 10 may be of any usual construction and provided with the usual end-cap 11, and spring 12 to support the battery 13 and make contact therewith. A conductor strip which serves to connect the zinc electrode of the battery with one end of the incandescent filament is shown at 14 and a gap in this conductor is bridged by any suitable switch 15.

The upper end of the casing 10 is provided with a threaded ring 16 which may be riveted or otherwise attached to the casing 10. Upon the threaded ring 16 is screwed the lamp-head 17 which carries the parabolic reflector 18, and the plane glass 19 attached thereto by means of the ring 20 in an obvious manner. Attached to reflector 18 at a point on its axis is a nipple 21 provided with a female thread. Encircling the nipple 21, behind the reflector is a ring 22 having the projecting arm 23, this member being best shown in Fig. 3. A distance piece 24 is interposed between ring 22 and reflector 18 so that when the ends of nipple 21 are upset, the arm 23 is rigidly positioned with respect to the reflector.

Within nipple 21 is a sleeve 25 having a male thread engaging the thread of the nipple and a female thread engaging the usual threaded base 26 of an incandescent bulb 27. In the opposite end of sleeve 25 is a thick disc of strong insulating material 28 rigidly attached to the sleeve by rolling the metal of the sleeve into an internally projecting rib in front of disc 28 and crimping the metal of the sleeve behind the disc 28.

Passing through disc 28 is a metal stud 29 which is firmly embedded in the disc 28 and insulated from sleeve 25 by the disc. The stud 29 is expanded at its lower end to form a shoulder which is in contact with the insulating disc and effectually prevents the stud 29 from sliding in the disc 28 under the influence of impacts against the expanded head, for a purpose hereafter described.

The terminal of the incandescent bulb is screwed against the stud 29 and the carbon terminal of the battery is normally held firmly against the expanded head of the stud by spring 12.

Soldered or otherwise rigidly attached to

the inner end of sleeve 25 is the scalloped metal disc 30, best shown in Fig. 2. Affixed to disc 30 is an upstanding pin 31 having a narrow notch 32 in one side, the pin and notch being so positioned with respect to arm 23 that the end of the arm 23 will pass through the notch at one stage of the relative rotation between the reflector and its attached arm 23 and the sleeve 25 and its 5 attached pin 31. If the reflector is held stationary and sleeve 25 is rotated one revolution in either direction from the position shown in Fig. 1, the arm 23 will strike pin 31 either above or below notch 32 and further rotation will be prevented. It will thus 10 be seen that when the sleeve 25 and attached parts are assembled, the movement of the incandescent bulb along the axis of the reflector is limited to a trifle less than twice 15 the pitch of the thread on sleeve 25.

In constructing the lamp, the notch 32 in pin 31 is so positioned that when the arm 23 registers with the notch, as shown in Fig. 1, a bulb of average dimensions will be 20 in proper relation to the reflector to secure a proper focus. To permit a focus to be obtained in spite of non-uniformity in the bulbs, the sleeve 25 may be rotated one revolution in either direction and this will 25 be sufficient to secure a focus.

The upper end of the conductor strip 14 is bent to contact with scalloped disc, and the bent portion of the strip 14 has sufficient resiliency to permit rotation of the disc, the 30 conductor strip following its contour and remaining in contact with it at all times. The lamp-head 17 may be locked in position after being screwed onto the ring 16 to the desired point by means of the locking ring 33 coaxing with the head 34 on ring 16. Upon screwing the locking ring 33 away 35 from the lower end of the lamp-head 17, the latter may be freely screwed onto the thread on ring 16. By holding the lamp-head 17 stationary with respect to ring 16 and turning locking ring 33 tightly against the bead 34, the threads on members 16 and 17 will be pressed together so tightly that 40 there will be no danger of the lamp-head being 45 accidentally displaced.

The operation and manner of assembling the flashlight is as follows: The lamp-head, reflector, plane glass 19, and the incandescent bulb are first assembled, the base of the bulb 50 being screwed into sleeve 25 as far as possible, and the arm 23 and notch 32 being in proper relation. The ring 33 is placed on the lamp-head 17 and screwed away from its lower end. The head is then screwed 55 onto the casing. The disc 30 will immediately engage the conductor strip 14 and be held against rotation, while the arm 23 swings around the axis of rotation and strikes the pin 31 below notch 32. Con-

tinued rotation of the head will then rotate 60 disc 30, the scallops slipping under the resiliency conductor strip 14. Rotation is continued until the head has reached or nearly reached the limit of its motion. By the time arm 23 strikes against the pin 31 below 65 the notch 32, any bulb which may have been inserted in sleeve 25 should be too far from the reflector to secure a perfect focus, and the continued rotation of the lamp-head after this point is reached, is only for the 70 purpose of securing a suitable connection between the lamp-head and the casing. The battery may advantageously be removed from the casing until the lamp-head reaches the desired point. The battery is then 75 placed in the casing, the end cap 11 applied, and the switch 15 manipulated to light the lamp. The lamp-head is then turned in such a direction that it will be unscrewed 80 from the casing while the beam of light from the lamp is directed toward a suitable surface to indicate when a focus has been reached. During this reverse movement of the lamp-head, the disc 30 will be held 85 against rotation by the conductor strip 14 and the arm 23 will swing around its axis of rotation, passing through notch 32, if the head is turned one complete revolution. The head may then be turned another revolution before the arm 23 strikes pin 31 above 90 the notch, and before this point is reached, a perfect focus will have been obtained. The locking ring 33 is then turned down tightly against the bead 34, thereby locking 95 the head in its existing position and preserving the focus of the lamp until the ring 33 is again moved to unlock the threaded connection.

Fig. 4 shows a modification of the invention in which a simplified construction is 100 used, but in which the lamp-head must be removed from the casing at any time when it is desired to adjust the bulb with respect to the reflector. The casing 10, end cap 11, spring 12 and switch 15, are arranged as 105 in the construction illustrated in Fig. 1, but parts are omitted for clearness of illustration. The lamp-head is also of similar construction to that of Fig. 1. However, the bulb-holding sleeve and certain of the parts 110 behind the reflector, are modified, and the locking ring 33 and the bead 34 of ring 16 are omitted, since in the modification shown in Fig. 4, the lamp-head is intended to be 115 screwed onto the casing to the limit of its motion at all times.

In the construction of Fig. 4, the ring 22 having the projection 23, is replaced by a cup which may have a flat bottom 35, and perpendicular sides 36 projecting away from 120 the reflector as shown in the drawing. The end of the conductor strip 14 engages the side wall of this cup and establishes electri- 125

cal connection with it. The scalloped disc 30 is replaced by an arm 37 attached to the sleeve 25 in any suitable way and having a turned over end 38 at such a distance 5 from the sleeve 25 that the end 38 will bear with sufficient friction against the inside of the wall 36 of the cup to hold the sleeve against accidental rotation with respect to the cup and the reflector to which it is attached, but at the same time permit the sleeve to be rotated with respect to the reflector if it is desired to change the adjustment of the lamp. The insulating disc 28 penetrated by a metallic conductor 29, is 10 preferably employed in the end of the sleeve 25 as in the lamp shown in Fig. 1.

The operation of this modification will be readily apparent. In order to focus the bulb, it is necessary to remove the lamp-head. 20 The sleeve 25 may then be readily rotated as desired and will be held in any desired position by the friction between the overturned end 38 of the arm 37 and the wall 36 of the cup. The lamp-head may be applied to the casing and battery momentarily, 25 without engaging the threads on the head and the casing, in order to test the accuracy of the adjustment. When a satisfactory focus is obtained, the lamp-head is screwed 30 onto the casing to the limit of its motion, the distance between the incandescent filament and the reflector remaining unchanged during this operation.

While the flashlights illustrated in the drawings are shown as having the battery-surrounding casing made of fiber or other insulating material, it is obvious that metallic casings may be used instead, using insulation where necessary in a manner well understood in the prior art. The construction herein shown is generally known as a "short circuiting" construction in that the lamp may be caused to light regardless of the position of the switch by establishing 40 an outside electrical connection between the end cap 11 and the lamp-head 17, as might be done for example, by placing the flashlight in a box of metal tools. If it is desired to make the flashlight non-short-circuiting, it is only necessary to interpose 50 suitable insulation at some point in the circuit which might thus be accidentally established, as for example between the reflector 18 and the nipple 21.

The purpose of the thick disc of insulating material 28 in the sleeve carrying the incandescent bulb, is to provide a buffer to prevent impacts, such as would be occasioned by dropping the battery into the flashlight, 60 from being transmitted to the base of the incandescent bulb, since the bulb is necessarily fragile, and a shock such as that above instanced would be likely to so damage the bulb that it would become useless. The manner of operation of the disc of insulating

material will be readily apparent, since there is no freedom of movement between the metal stud and the insulating material surrounding it, or between the insulating material and the sleeve into which it is fastened. 70 Any impact received upon the metal stud will be transmitted to the insulating disc and thence to the sleeve 25, the nipple 21, the reflector 18, lamp-head 17 and casing 10. So long as there is no flexure of the disc due to 75 such impact, no pressure can be brought upon the base of the incandescent bulb, and since the disc is of small diameter and is relatively thick, it can readily be made so stiff that no flexure will take place. 80

The type of buffer or shock-absorber herein disclosed, cooperates with the focusing device in an exceptional manner in that the buffer is moved with the bulb in focussing the light and is at all times in 85 contact with the terminal of the lamp and in an effective position. The shock-absorbing devices of the prior art which were rigidly attached to the lamp-head or reflector could not be used with a focussing device, 90 since movement of the bulb in one direction would, in general be prevented by the buffer or shock-absorber, while movement in the other direction would break the contact between the bulb and the battery, and render 95 it impossible to light the lamp. In addition to this advantage, the buffer herein described eliminates all springs such as have heretofore been interposed between the bulb and the battery and provides an unusually 100 strong and positive protection for the base of the incandescent bulb.

While the invention has been illustrated by certain specific embodiments and in connection with certain illuminating devices, 105 it is by no means limited to any of the specific forms and arrangements herein illustrated and described, but is capable of extensive modification and is adapted to illuminating devices of great variety. 110

My invention is, therefore, limited only as required by the language of the appended claims.

I claim:

1. In a portable electric lamp, a casing, a battery contained therein, a bulb-holder containing an electric bulb, said bulb-holder being movable for focussing, and a buffer arranged to receive the impact of the battery, 115 said buffer being carried by said bulb-holder. 120

2. In a portable electric lamp, a casing, a battery contained therein, a reflector, a bulb-holder arranged for movement with respect to the reflector, an electric bulb mounted in 125 the bulb-holder, and a buffer, arranged to receive the impact of the battery, said buffer being carried by the bulb-holder.

3. In a portable electric lamp, a casing, a battery contained therein, a reflector, a bulb- 130

holder adapted to move along a screw thread, an electric bulb mounted in the bulb-holder, and a buffer arranged to receive the impact of the battery, said buffer being rigidly attached to said bulb-holder.

4. In a portable electric lamp, a casing, a battery contained therein, a reflector, a threaded socket mounted in fixed relation to the reflector, an externally threaded sleeve 10 mounted for rotary and longitudinal motion in the threaded socket, an electric bulb mounted in said sleeve, and a buffer arranged to receive the impact of the battery, said buffer being rigidly attached to the 15 bulb-containing sleeve.

5. In a portable electric lamp, a casing, a battery contained therein, a reflector, a threaded boss on the axis of said reflector, an externally threaded sleeve mounted for 20 rotary and longitudinal motion in said threaded boss, an electric bulb mounted in the sleeve, and a buffer arranged to receive the impact of the battery, said buffer comprising a strong disc of insulating material 25 arranged transversely of said threaded sleeve and rigidly attached to the sleeve.

6. In an illuminating device comprising a battery, an internally threaded socket, an externally threaded bulb-holder mounted 30 for rotary longitudinal motion in said socket, and an electric bulb mounted in said bulb-holder in fixed relation thereto and a conductive member placing said bulb in circuit with said battery and rigidly mounted to 35 protect the bulb from impacts directed toward its base.

7. In an illuminating device, a reflector, an internally threaded socket, an externally threaded bulb-holder mounted for rotary 40 and longitudinal motion within said socket, an electric bulb mounted in the bulb-holder, and a plate having a serrated margin rigidly secured to said holder and adapted to cooperate with a holding member, for preventing 45 accidental displacement of said bulb-holder in said socket.

8. In a portable electric lamp, a casing, a reflector carried thereby, an internally threaded socket in said reflector, an externally threaded bulb-holder mounted for rotary and longitudinal motion within said socket, an electric bulb mounted in the bulb-holder, a serrated member secured to said bulb-holder, and a contact strip attached to 55 the casing and having a resilient end adapted to engage the serrated member to hold the same in position.

9. In a flashlight, a casing adapted to receive a battery, an apertured reflector mounted for rotary and longitudinal movement on said casing, a rotatable bulb-holder mounted in the aperture of the reflector and in fixed relation to the casing, and means for restraining rotation of the holder during 60 longitudinal adjustment of the reflector, 65

whereby the relation of the holder and reflector may be varied.

10. In an illuminating device, a casing, a head member carrying a reflector and mounted for movement with respect to said casing, a bulb-holder mounted in the reflector, means for restraining movement of the holder with the reflector, said head member having a tubular threaded extension engaging an end of the casing, and means for locking the head member in position, comprising a ring threaded upon said extension.

11. In an illuminating device, a reflector, an internally threaded socket rigidly attached to said reflector, an externally threaded bulb-holder mounted for rotary and longitudinal motion in said socket, an electric bulb mounted in said bulb-holder in fixed relation thereto, and means for effecting the longitudinal adjustment of said internally 85 threaded socket while preventing the rotation of said bulb-holder.

12. In an illuminating device, a reflector, an internally threaded socket rigidly attached to said reflector, an externally threaded bulb-holder mounted for rotary and longitudinal motion in said socket, an electric bulb mounted in said bulb-holder in fixed relation thereto and means for effecting the longitudinal adjustment of said internally 95 threaded socket and for preventing rotation of said bulb-holder during a limited portion of the rotation of said socket.

13. In an illuminating device, a reflector, an internally threaded socket rigidly attached to said reflector, an externally threaded bulb-holder mounted for rotary and longitudinal motion in said socket, an electric bulb mounted in said bulb-holder in fixed relation thereto, means for rotating said 100 internally threaded socket, and means for preventing rotation of said bulb-holder during a limited portion of the rotation of said socket, and permitting rotation of the bulb-holder during other portions of the rotation 105 of said socket.

14. In a hand lamp, the combination of a casing, a battery therein, a lamp, a support for said lamp, and a reflector rotatable on said support to move axially of said casing.

15. In a hand lamp, the combination of a casing, a battery therein, a lamp, a support for said lamp, and a reflector threaded to said support and rotatable thereon to move axially of said casing, and thereby change 120 the spread of the beam of light from said hand lamp.

16. In a hand lamp, the combination of a casing, a battery therein, a lamp, a support for said lamp, a reflector rotatable on said support to move axially of said casing, and means adapted for holding said reflector against inadvertent rotation.

17. In a hand lamp, the combination of a casing, a battery therein, a lamp support 130

against which said battery bears and a reflector rotatable on said support to move axially of said casing.

18. In a hand lamp, the combination of a source of current; a lamp in circuit therewith; a lamp holder for said lamp, said lamp holder having an externally threaded part; a tubular casing inclosing said source of current, lamp and lamp holder; a reflector mounted at one end of said casing and coaxial therewith, said reflector cooperating with said lamp; and threaded means cooperating with said externally threaded part to adjust said lamp and said reflector relatively to one another axially of said casing to change the spread of the reflected beam from said lamp.

19. In a hand lamp, the combination of a battery; a lamp; an externally threaded lamp holder therefor bearing against and in circuit with said battery; impact buffing means associated with said lamp holder; a casing carrying said battery, lamp holder and lamp in axial alinement; a reflector coaxial with said casing and cooperating with said lamp; and threaded means cooperating with such external thread to effect relative adjustment of said lamp holder and said reflector axially of said casing to change the spread of the reflected beam from said lamp.

20. In a hand lamp, the combination, of a tubular casing; a battery therein; a lamp in said casing; a lamp holder having a threaded part holding said lamp and a second threaded part carried thereby; a reflector adjacent one end of said casing and coaxial with said battery and said lamp; and threaded means cooperating with said second threaded part to effect relative adjustment of said reflector and said lamp holder axially of said casing to change the spread of the reflected beam from said lamp.

21. In a hand lamp, the combination of a casing; a battery therein; a lamp in said casing; an adjustable lamp holder having a threaded part receiving said lamp, and a second threaded part movable with said lamp holder; a reflector in said casing cooperating with said lamp; and threaded means connected to said reflector and adapted to cooperate with said second threaded part to effect relative adjustment of said reflector and said lamp holder axially of said casing to change the spread of the reflected beam from said lamp.

22. In a hand lamp, the combination of a battery, a lamp, a holder therefor, impact buffing means between said lamp and said battery, a reflector cooperating with said lamp, a tubular casing enclosing the aforesaid elements in axial alinement, and means whereby said reflector and said holder are relatively adjustable to alter the spread of the reflected beam from said lamp.

23. In a hand lamp, the combination of a battery; a lamp; a lamp holder therefor having an externally threaded part; a tubular casing enclosing said battery, lamp and holder and carrying them in axial alinement with the longitudinal axis of said tubular casing; a reflector in said casing cooperating with said lamp; and threaded means adapted to cooperate with said externally threaded part to effect relative adjustment of said reflector and lamp holder along said axis to change the spread of the reflected beam from said lamp.

24. In a hand lamp, the combination of a battery; a lamp; a holder therefor having a laterally extending conductive member; a tubular casing carrying said battery, lamp and holder in axial alinement with the longitudinal axis of said tubular casing; a reflector in said casing cooperating with said lamp; means for effecting relative adjustment of said holder and reflector axially of said casing to alter the spread of the reflected beam from said lamp, and a conductor in said casing having a part maintained in engagement with said member during such relative adjustment.

25. In a hand lamp, the combination of a casing, a battery therein, a reflector therein, a lamp cooperating therewith, a holder therefor, means whereby said lamp holder and reflector are adjustable relatively to one another to alter the spread of the reflected beam, comprising a serrated disc carried by said holder, and means adapted to engage such serrations to control the movement of said holder.

26. In a hand lamp, the combination of a battery; a lamp; a holder therefor; a reflector cooperating with said lamp; said reflector and holder being relatively adjustable; a tubular casing carrying said battery, lamp, holder and reflector in axial alinement with the longitudinal axis of said casing; and comprising means whereby said reflector and holder are axially adjustable relatively to one another to alter the spread of the reflected beam from said lamp; and means for retaining such adjusting means in any one of its adjusted positions.

27. In a hand lamp, the combination of a battery; a lamp; a holder therefor; a reflector cooperating with said lamp; said reflector and holder being relatively adjustable; a casing enclosing said battery, lamp, holder and reflector, and comprising means whereby said reflector and holder are axially adjustable relatively to one another to alter the spread of the reflected beam from said lamp; and a ring encircling said casing for retaining such adjusting means in any one of its adjusted positions.

In testimony whereof, I affix my signature.
LEE J. VOORHEES.
